(57) **ABSTRACT**

A golf club head including a striking face, a sole extending aft from the striking face, a crown extending aft from the striking face, a skirt extending between the sole and the crown, an interior cavity defined by the striking face, the sole, the crown, and the skirt, an aperture formed through the sole, the aperture having an aperture length and an aperture width, wherein the aperture length is substantially larger than the aperture width, and a stiffening member affixed to the sole, wherein a portion of the stiffening member resides within the aperture, wherein the sole is constructed of a first material having a first density, the stiffening member is constructed of a second material having a second density, and wherein the second density is at least 30% less than the first density.

GOLF CLUB HEAD

TECHNICAL FIELD

This present technology generally relates to systems, devices, and methods related to golf clubs, and more specifically to new and improved metalwood golf clubs having a stiffening member.

DESCRIPTION OF THE RELATED TECHNOLOGY

The complexities of golf club design are well known. The specifications for each component of the club (i.e., the club head, shaft, grip, and subcomponents thereof) directly impact the performance of the club. Thus, by varying the design specifications, a golf club can be tailored to have specific performance characteristics.

The design of club heads has long been studied. Among the more prominent considerations in club head design are loft, lie, face angle, horizontal face bulge, vertical face roll, center of gravity (CG), inertia, material selection, and overall head weight. While this basic set of criteria is generally the focus of golf club engineering, several other design aspects must also be addressed. The interior design of the club head may be tailored to achieve particular characteristics, such as the inclusion of hosel or shaft attachment means, perimeter weights on the club head, and fillers within hollow club heads.

Golf club heads must also be strong to withstand the repeated impacts that occur during collisions between the golf club and the golf ball. The loading that occurs during this transient event can create a peak force of over 2,000 lbs. Thus, a major challenge is designing the club face and body to resist permanent deformation or failure by material yield or fracture.

Players generally seek a metal wood driver and golf ball combination that delivers maximum distance and landing accuracy. The distance a ball travels after impact is dictated by the magnitude and direction of the ball's translational velocity and the ball's rotational velocity or spin. Environmental conditions, including atmospheric pressure, humidity, temperature, and wind speed, further influence the ball's flight. However, these environmental effects are beyond the control of the golf equipment manufacturer. Golf ball landing accuracy is driven by a number of factors as well. Some of these factors are attributed to club head design, such as center of gravity and club face flexibility.

Technological breakthroughs in recent years provide the average golfer with more distance, such as making larger head clubs while keeping the weight constant or even lighter, by casting consistently thinner shell thickness and going to lighter materials such as titanium or composites.

However, despite the potential gains in the discretionary mass gained by the utilization of thinner constructions and lightweight materials, they usually come with some drawbacks. More specifically, they may generally come with an undesirable acoustic characteristic at impact, making the golf club undesirable to a golfer irrespective of performance. U.S. Pat. No. 6,612,938 to Murphy et al. illustrates one of the earlier attempts to use exotic materials in a golf club head such as plies of pre-preg material. One method of improving the acoustic signature of the golf club head is to stiffen the club head using stiffening members, such as those disclosed in U.S. Pat. No. 9,498,688 to Galvan et al. U.S. Pat. No. 8,651,975 to Soracco provided another example of an attempt to address the acoustic characteristics associated

with golf clubs that utilizes exotic material. More specifically, Soracco provided a golf club head with sound tuning composite members forming at least a portion of the surface of the golf club head. Finally, U.S. Pat. No. 8,849,635 to Hayase et al. went above and beyond the mere basic design of a golf club head for acoustic characteristics and even made an attempt to predict modal damping ratio of composite golf club heads.

Despite the above, none of the references provide a method to improve the performance of a golf club head by providing a way to improve the performance of a golf club head utilizing advanced materials all while providing a clean way to address the degradation of the acoustic characteristics of the golf club head. Hence, it can be seen from the above that a golf club design that is capable of achieving both of the goal of incorporating lightweight constructions in order to increase discretionary mass as well as achieving a desirable acoustic characteristic while minimizing the undesirable sound and feel of the golf club head. The present invention provides novel solutions for improving the stiffness and acoustic characteristics of a golf club head at impact.

SUMMARY

The systems, methods, and devices described herein have innovative aspects, no single one of which is indispensable or solely responsible for their desirable attributes. Without limiting the scope of the claims, some of the advantageous features will now be summarized.

The present invention relates to a golf club head including a stiffening member that alters the compliance characteristics as compared to known golf club heads.

One non-limiting embodiment of the present technology includes a golf club head, including a striking face, an aft portion extending aft from the striking face; the aft portion including: a sole defining a lower surface of the golf club head and extending aft from the striking face; a crown defining an upper surface of the golf club head and extending aft from the striking face; a skirt extending between the sole and the crown; a hosel extending from the crown; an interior cavity defined by the striking face, the sole, the crown, and the skirt; a recessed portion formed in an exterior of the aft portion; an aperture formed through the recessed portion of the aft portion, the aperture having an aperture length and an aperture width, wherein the aperture length is substantially larger than the aperture width; and a stiffening member affixed to the aft portion; wherein a portion of the stiffening member resides within the aperture; wherein the stiffening member comprises an internal portion and an external portion, wherein the external portion is oriented substantially perpendicular to the internal portion; wherein the internal portion extends through the aperture into the interior cavity and wherein the external portion abuts the recessed portion.

An additional non-limiting embodiment of the present technology includes a golf club head, including: a striking face, a sole defining a lower surface of the golf club head and extending aft from the striking face; a crown defining an upper surface of the golf club head and extending aft from the striking face; a skirt extending between the sole and the crown; a hosel extending from the crown; an interior cavity defined by the striking face, the sole, the crown, and the skirt; an aperture formed through the sole, the aperture having an aperture length and an aperture width, wherein the aperture length is substantially larger than the aperture width; and a stiffening member affixed to the sole; wherein

a portion of the stiffening member resides within the aperture; wherein the sole is constructed of a first material having a first density, the stiffening member is constructed of a second material having a second density, and wherein the second density is at least 30% less than the first density.

In an additional non-limiting embodiment of the present technology the stiffening member comprises a stiffening member length measured along the major axis of the stiffening member, a stiffening member height measured perpendicularly to the stiffening member length and extending into the interior cavity, and a stiffening member width measured perpendicularly to the stiffening member length and the stiffening member height, wherein the stiffening member height is at least twice the stiffening member width and wherein the stiffening member length is at least five times the stiffening member height.

In an additional non-limiting embodiment of the present technology the first material has a first modulus of elasticity, the second material has a second modulus of elasticity, and wherein the second modulus of elasticity is at least 30% greater than the first modulus of elasticity.

In an additional non-limiting embodiment of the present technology the stiffening member is constructed from carbon fiber reinforced polymer and affixed to the sole with adhesive.

In an additional non-limiting embodiment of the present technology the sole comprises a recessed portion in an exterior of the sole along the aperture.

In an additional non-limiting embodiment of the present technology the stiffening member comprises an internal portion and an external portion, wherein the external portion is oriented substantially perpendicular to the internal portion.

In an additional non-limiting embodiment of the present technology the internal portion extends through the aperture into the interior cavity and wherein the external portion abuts the recessed portion.

In an additional non-limiting embodiment of the present technology the sole further comprises a retention protrusion extending the interior cavity, wherein the stiffening member abuts the retention protrusion.

In an additional non-limiting embodiment of the present technology the stiffening member comprises a weight receptacle and a weight member residing within the weight receptacle.

An additional non-limiting embodiment of the present technology includes a second stiffening member affixed to the crown, the second stiffening member arranged parallel to the stiffening member.

An additional non-limiting embodiment of the present technology includes a golf club head, including: a striking face, a sole defining a lower surface of the golf club head and extending aft from the striking face; a crown defining an upper surface of the golf club head and extending aft from the striking face; a skirt extending between the sole and the crown; a hosel extending from the crown; an interior cavity defined by the striking face, the sole, the crown, and the skirt; an aperture formed through the sole, the aperture having an aperture length and an aperture width, wherein the aperture length is substantially larger than the aperture width; and a stiffening member affixed to the sole; wherein a portion of the stiffening member resides within the aperture; wherein the stiffening member comprises a stiffening member length measured along the major axis of the stiffening member, a stiffening member height measured perpendicularly to the stiffening member length and extending into the interior cavity, and a stiffening member width measured

perpendicularly to the stiffening member length and the stiffening member height, wherein the stiffening member height is at least twice the stiffening member width and wherein the stiffening member length is at least five times the stiffening member height; wherein the sole is constructed of a first material having a first modulus of elasticity, wherein the stiffening member is constructed of a second material having a second modulus of elasticity, and wherein the second modulus of elasticity is at least 30% greater than the first modulus of elasticity.

In an additional non-limiting embodiment of the present technology the first material has a first density, the second material has a second density, and wherein the second density is at least 30% less than the first density.

In an additional non-limiting embodiment of the present technology the stiffening member is constructed from carbon fiber reinforced polymer and affixed to the sole with adhesive.

In an additional non-limiting embodiment of the present technology the sole comprises a recessed portion in an exterior of the sole along the aperture.

In an additional non-limiting embodiment of the present technology the stiffening member comprises an internal portion and an external portion, wherein the external portion is oriented substantially perpendicular to the internal portion.

In an additional non-limiting embodiment of the present technology the internal portion extends through the aperture into the interior cavity and wherein the external portion abuts the recessed portion.

In an additional non-limiting embodiment of the present technology the sole further comprises a retention protrusion extending the interior cavity, wherein the stiffening member abuts the retention protrusion.

In an additional non-limiting embodiment of the present technology the stiffening member comprises a weight receptacle and a weight member residing within the weight receptacle.

An additional non-limiting embodiment of the present technology includes a second stiffening member affixed to the crown, the second stiffening member arranged parallel to the first stiffening member.

This summary is provided to introduce a selection of concepts in a simplified form that are further described below in the Detailed Description. This summary is not intended to identify key features or essential features of the claimed subject matter, nor is it intended to be used to limit the scope of the claimed subject matter.

BRIEF DESCRIPTION OF THE DRAWINGS

The accompanying drawings form a part of the specification and are to be read in conjunction therewith. The illustrated embodiments, however, are merely examples and are not intended to be limiting. Like reference numbers and designations in the various drawings indicate like elements.

FIG. 1 illustrates a perspective view of a golf club head.

FIG. 2 illustrates an additional perspective view of the golf club head of FIG. 1 with a stiffening member and a portion of the crown missing for illustrative purposes.

FIG. 3 illustrates a cross sectional view A-A' of the golf club head of FIG. 2.

FIG. 4 illustrates a cross sectional view B-B' of the golf club head of FIG. 2.

FIG. 5 illustrates a perspective view of the sole of golf club head of FIG. 1 including a partially installed stiffening member.

FIG. 6 illustrates an additional embodiment of the golf club head with the stiffening member not yet installed.

FIG. 7 illustrates an additional perspective view of a golf club head, with a portion of the crown missing for illustrative purposes, the golf club head including an additional embodiment of a stiffening member.

FIG. 8 illustrates a cross sectional view of a golf club head including an additional embodiment of a stiffening member.

FIG. 9 illustrates an additional cross-sectional view of the golf club head of FIG. 8.

FIG. 10 illustrates an additional embodiment of a golf club head.

DETAILED DESCRIPTION

In the following detailed description, reference is made to the accompanying drawings, which form a part of the present disclosure. The illustrative embodiments described in the detailed description, drawings, and claims are not meant to be limiting. Other embodiments may be utilized, and other changes may be made, without departing from the spirit or scope of the subject matter presented herein. It will be readily understood that the aspects of the present disclosure, as generally described herein, and illustrated in the Figures, can be arranged, substituted, combined, and designed in a wide variety of different configurations, all of which are explicitly contemplated and form part of this disclosure. For example, a system or device may be implemented or a method may be practiced using any number of the aspects set forth herein. In addition, such a system or device may be implemented or such a method may be practiced using other structure, functionality, or structure and functionality in addition to or other than one or more of the aspects set forth herein. Alterations and further modifications of inventive features illustrated herein, and additional applications of the principles of the inventions as illustrated herein, which would occur to one skilled in the relevant art and having possession of this disclosure, are to be considered within the scope of the invention.

Other than in the operating examples, or unless otherwise expressly specified, all of the numerical ranges, amounts, values and percentages such as those for amounts of materials, moments of inertias, center of gravity locations, loft and draft angles, and others in the following portion of the specification may be read as if prefaced by the word "about" even though the term "about" may not expressly appear with the value, amount, or range. Accordingly, unless indicated to the contrary, the numerical parameters set forth in the following specification and attached claims are approximations that may vary depending upon the desired properties sought to be obtained by the present invention. At the very least, and not as an attempt to limit the application of the doctrine of equivalents to the scope of the claims, each numerical parameter should at least be construed in light of the number of reported significant digits and by applying ordinary rounding techniques.

Notwithstanding that the numerical ranges and parameters setting forth the broad scope of the invention are approximations, the numerical values set forth in the specific examples are reported as precisely as possible. Any numerical value, however, inherently contains certain errors necessarily resulting from the standard deviation found in their respective testing measurements. Furthermore, when numerical ranges of varying scope are set forth herein, it is contemplated that any combination of these values inclusive of the recited values may be used.

In describing the present technology, the following terminology may have been used: The singular forms "a," "an," and "the" include plural referents unless the context clearly dictates otherwise. Thus, for example, reference to an item 5 includes reference to one or more items. The term "plurality" refers to two or more of an item. The term "substantially" means that the recited characteristic, parameter, or value need not be achieved exactly, but that deviations or variations, including for example, tolerances, measurement error, measurement accuracy limitations and other factors known to those of skill in the art, may occur in amounts that do not preclude the effect the characteristic was intended to provide. A plurality of items may be presented in a common 10 list for convenience. However, these lists should be construed as though each member of the list is individually identified as a separate and unique member. Thus, no individual member of such list should be construed as a de facto equivalent of any other member of the same lists solely 15 based on their presentation in a common group without indications to the contrary. Furthermore, where the terms "and" and "or" are used in conjunction with a list of items, they are to be interpreted broadly, in that any one or more of the listed items may be used alone or in combination with 20 other listed items. The term "alternatively" refers to a selection of one of two or more alternatives, and is not intended to limit the selection of only those listed alternative 25 or to only one of the listed alternatives at a time, unless the context clearly indicated otherwise.

Features of the present disclosure will become more fully 30 apparent from the following description and appended claims, taken in conjunction with the accompanying drawings. After considering this discussion, and particularly after 35 reading the section entitled "Detailed Description" one will understand how the illustrated features serve to explain certain principles of the present disclosure.

FIG. 1 illustrates a perspective view of a golf club head 100 in accordance with the present invention. The golf club head 100 illustrated is a metal wood golf club head, and 40 more specifically a driver with a volume of approximately 460 cc's. However, the inventions described herein can be applied to other metal wood golf club heads including fairways and hybrids. Additionally, the inventions described herein may further be included in iron type golf club heads 45 as well. The golf club head 100 provides only a rough sketch of the external components of the golf club head 100 without illustrating the internal workings of the golf club head 100. More specifically, the golf club head 100 has a striking face 102 at a frontal portion of the golf club head 100, the striking face 102 configured to strike a golf ball (not illustrated). The golf club head also includes a sole 104 extending aft from a 50 lower portion of the striking face 102. The intersection of the striking face 102 and the sole 104 forms the sole return 106. The golf club 100 head also includes a crown 108 extending aft from an upper portion of the striking face 102. The intersection of the striking face 102 and the crown 108 forms the crown return 118. The intersection of the sole 104 and 55 the crown 108 forms a skirt 110 which extends around the aft perimeter of the golf club head 100. The golf club head 100 includes a hosel 112 extending out of the heel portion 114 of the club head 100, the hosel configured to receive a shaft (not illustrated), the heel portion being opposite the toe portion 116. FIG. 1 also includes a coordinate system 60 wherein the z axis extends forward, parallel to a ground plane when the golf club head 100 is in an address position, an x axis perpendicular to the z-axis, and extending heel-wards parallel to a ground plane when the golf club head 100

is in an address position, and substantially parallel to the striking face, and a y-axis perpendicular to the z-axis and x-axis.

FIG. 2 illustrates an additional perspective view of the golf club head 100 of FIG. 1 with a stiffening member and with a portion of the crown 108 missing for illustrative purposes. The interior 120 of the golf club head 100 is visible in FIG. 2. As illustrated in FIG. 2, the golf club head 100 also includes a stiffening member 200 affixed to the sole 104 of the golf club head 100. In the illustrated embodiment, a majority of the golf club head 100, including the sole 104, is formed from a metal material, and more specifically in the illustrated embodiment, titanium. In other embodiments, portions of the golf club head 100 may be formed of non-metal materials such as carbon fiber composites. In the illustrated embodiment, the stiffening member 200 is formed separately from the sole 104 and subsequently affixed to the sole 104.

The stiffening member 200 can be installed into the interior 120 in a variety of ways. In one embodiment, the golf club head 100 might have composite portions such as the crown which are affixed to the golf club head 100 after installation of the stiffening member 200, allowing the stiffening member 200 to be installed in interior of the golf club head 100 prior to final assembly of the golf club head 100.

FIG. 3 illustrates a cross sectional view A-A' of the golf club head of FIG. 2. In an additional embodiment, as illustrated in FIG. 3, the golf club head 100 can include an aperture 130 configured to receive the stiffening member. More specifically, the sole 104 can include the aperture 130. The stiffening member 200 can be installed through the aperture 130 and reside within the aperture 130 when it is affixed to the golf club head 100. The golf club head 100 can also include a recessed portion 140 to receive a portion of the stiffening member 200. The stiffening member 200 can include a internal portion 210 residing primarily within the interior 120 of the golf club head 100 and an external portion 220 residing primarily within the recessed portion 140 of the golf club head 100. In the illustrated embodiment, the external portion 220 is oriented substantially perpendicular to the internal portion 210. The recessed portion 140 includes a recessed wall 142. The aperture 130 is formed through the recessed wall 142. Additionally, the internal portion 210 of the stiffening member 200 abuts the recessed wall 142. In some embodiments, adhesive can be applied between the external portion 220 and the recessed wall 142. In some embodiments, adhesive can be applied between the stiffening member 200 and the edges 132 of the aperture 130. As illustrated, the recessed portion 140 can be configured such that the stiffening member 200 does not protrude past the outer extend of the sole 104.

FIG. 4 illustrates a cross sectional view B-B' of the golf club head of FIG. 2. In an additional embodiment, as illustrated in FIG. 4, the golf club head 100 can include one or more receptacles 150 in the interior 120 of the golf club head 100 configured to receive and retain the stiffening member 200. As illustrated in FIGS. 2 and 4, a receptacle 150 can include a first retention protrusion 151 and a second retention protrusion 152 configured to sandwich the stiffening member 200. In some embodiments, adhesive can be applied between the stiffening member 200 and the sole 104. In some embodiments, adhesive can be applied between the stiffening member and the retention protrusions 151, 152 of the receptacle 150. In other embodiments, no adhesive is applied between the stiffening member 200 and the receptacle 150. In other embodiments, the receptacle 150 only

includes a single retention protrusion 151. In other embodiments, the first retention protrusion 151 can be offset lengthwise along the stiffening member 200 from the second retention protrusion 152.

5 In some embodiments, as illustrated in FIGS. 2-4, the golf club head 100 can include an aperture 130, a recessed portion 140, and a receptacle 150 to retain a stiffening member. FIG. 5 illustrates a perspective view of the sole 104 of golf club head 100 of FIG. 1 including a partially installed 10 stiffening member 200. The aperture 130 allows the stiffening member 200 to be installed from the exterior of the golf club head 100. As illustrated in FIGS. 2-5, the stiffening member can include a first portion 201 which includes an internal portion 210 and an external portion 220 and a 15 second portion 202 which only includes an internal portion 210. The first portion 201 of the stiffening member 200 can have a length substantially similar to the length of the aperture 130 and recessed portion 140. As illustrated in FIG. 5, the stiffening member 200 can be rotated relative to its 20 final mounting orientation and the second portion 202 of the stiffening member can be installed through the aperture 130 and then the stiffening member 200 can be rotated into its final mountain mounting orientation such that the second portion 202 resides within the receptacle 150 and the external portion 220 of the first portion 201 resides within the recessed portion 140 as illustrated in FIGS. 2-4.

FIG. 6 illustrates an additional embodiment of the golf club head 100 with the stiffening member 200 not yet installed. As illustrated in FIG. 6, the aperture 130 can 30 extend the full length of the stiffening member 200. In an additional embodiment, the recessed portion 140 could run the full length of the aperture 130 and the stiffening member 200 could include an external portion 220 which extends along the entire length of the stiffening member 200.

35 The stiffening member 200 illustrated in FIGS. 2-6 stiffens the sole 104 it is affixed to and improves the acoustic signature of the golf club head 100 at impact. Additionally, the external portion 220 of the stiffening member 200 can 40 also provide a contrasting color on the exterior of the golf club head 100, improving the aesthetic of the golf club head 100 and providing visible technology for the golfer to enjoy. In one embodiment, the stiffening member 200 could be 45 customized in color or possibly in pattern or text to designate different club characteristics to appeal to different groups or even individual golfers.

As illustrated in FIGS. 2 and 4 the stiffening member 200 has a length L measured along its major axis, a height H measured perpendicular to the length L extending into the interior 120 of the golf club head 100, and a width W measured perpendicularly to the height H and length L. In one embodiment the height H is at least twice the width W and the length L is at least 5 times the height H. In other embodiments, the stiffening member 200 can be affixed to other or additional portions of the golf club head such as the skirt, crown, striking face, hosel, etc. In one embodiment the width W of the stiffening member 200 is approximately 1.0 mm. In another embodiment the width W of the stiffening member 200 is approximately 1.4 mm.

As mentioned above, the stiffening member 200 can be 60 adhered to the golf club head 100 utilizing adhesive. In other embodiments, the golf club head 100 and the stiffening member 200 can include complementary features such that the stiffening member 200 can snap into the golf club head 100 without the need for additional adhesives or mechanical locking features.

65 By manufacturing the stiffening member 200 separately from the rest of the golf club head 100 it can be made from

different materials which may have higher stiffness properties and/or a lower density. The stiffening member 200 can be made from, for example, composite, carbon fiber infused polymer, thermoplastic, thermoplastic composite, titanium, steel, stainless steel, magnesium, ceramic, aluminum-boron carbide, boron carbide, aluminum, etc.

Stiffness of a material depends on its modulus of elasticity, also known as Young's modulus. It is preferable that the stiffening member 200 have a higher modulus of elasticity than the portion of the golf club head 100 it is affixed to, the sole 104 for example. It is also preferable for the stiffening member 200 to have a lower density than the portion of the golf club head 100 it is affixed to. Golf club head 100, for example, can be formed from titanium with a modulus of elasticity of approximately 113 GPa and a density of approximately 4.5 g/cm³. The stiffening member 200, for example, can be formed from carbon fiber reinforced polymer with a modulus of elasticity of approximately 181 GPa and a density of approximately 1.5 g/cm³. In one embodiment the stiffening member has a density of less than 4.0 g/cm³. In one embodiment the stiffening member has a modulus of elasticity of greater than 120 GPa.

In one embodiment the stiffening member 200 has a modulus of elasticity at least 20% greater than the modulus of elasticity of the portion of the golf club head it is affixed to. In one embodiment the stiffening member 200 has a modulus of elasticity at least 30% greater than the modulus of elasticity of the portion of the golf club head it is affixed to. In one embodiment the stiffening member 200 has a modulus of elasticity at least 40% greater than the modulus of elasticity of the portion of the golf club head it is affixed to. In one embodiment the stiffening member 200 has a modulus of elasticity at least 50% greater than the modulus of elasticity of the portion of the golf club head it is affixed to.

In one embodiment the stiffening member 200 has a density that is at least 20% less than the density of the portion of the golf club head it is affixed to. In one embodiment the stiffening member 200 has a density that is at least 30% less than the density of the portion of the golf club head it is affixed to. In one embodiment the stiffening member 200 has a density that is at least 40% less than the density of the portion of the golf club head it is affixed to. In one embodiment the stiffening member 200 has a density that is at least 50% less than the density of the portion of the golf club head it is affixed to. In one embodiment the stiffening member 200 has a density that is at least 60% less than the density of the portion of the golf club head it is affixed to.

It is preferable for a composite stiffening member 200 to have the fibers aligned primarily in a lengthwise direction along its length to resist bending and provide stiffness to the golf club head. The modulus of the stiffening member 200 material should be taken of a sample with fibers oriented and loaded in a similar manner as it is in the golf club head 100.

FIG. 7 illustrates an additional perspective view of a golf club head 100, with a portion of the crown missing for illustrative purposes, the golf club head 100 including an additional embodiment of a stiffening member 200. As illustrated in FIG. 7, the stiffening member 200 includes a first weight receptacle 231 in a first portion 201 of the stiffening member 200, a second weight receptacle 232 in a second portion 202 of the stiffening member 200, and a weight member 230 residing within the second weight receptacle 232. The weight member 230, first weight receptacle 231, and second weight receptacle 232 are configured such that the weight member 230 can be installed in either the first weight receptacle 231 or the second weight recep-

tacle 232, altering the center of gravity location of the golf club head. In other embodiments, the golf club head 100 could include a plurality of stiffening members 200, further expanding the possibilities of adjusting the center of gravity location of the golf club head.

FIG. 8 illustrates a cross sectional view of a gold golf club head 300 including an additional embodiment of a stiffening member 400. FIG. 9 illustrates an additional cross-sectional view of the golf club head 300 of FIG. 8. The golf club head 300 of FIGS. 8 and 9 include a stiffening member 400 which extends around the golf club head 300 in a loop and is affixed to the sole 304, the skirt 310, and the crown 308. In one embodiment, the stiffening member 400 can be formed in one piece and extending around a majority of the golf club head 300. As illustrated in FIG. 8, the stiffening member 400 can reside within a receptacle 350.

FIG. 10 illustrates an additional embodiment of the golf club head 300. The golf club head 300 illustrated in FIG. 10 also includes stiffening members 400A, 400B affixed to both the sole 304 and the crown 308, however rather than one continuous stiffening member, this embodiment includes a first stiffening member 400A and a second stiffening member 400B. Each of these stiffening members 400A, 400B are similar in design to the stiffening member 200 of FIGS. 2-4. The first stiffening member 400A is affixed to the sole 304 and the second stiffening member 400B is affixed to the crown 308. As illustrated, the first stiffening member 400A and the second stiffening member 400B can be arranged parallel to one another such that they are substantially coplanar. The golf club head includes apertures 330 to receive the internal portions 410 of the stiffening members 400A, 400B and recessed portions 340 to receive the external portions 420 of the stiffening members 400A, 400B. In another embodiment the first stiffening member 400A could be affixed to the heel side of both the sole 304 and crown 308 and the second stiffening member 400B could be affixed to the toe side of both the sole 304 and the crown 308.

In describing the present technology herein, certain features that are described in the context of separate implementations also can be implemented in combination in a single implementation. Conversely, various features that are described in the context of a single implementation also can be implemented in multiple implementations separately or in any suitable sub combination. Moreover, although features may be described above as acting in certain combinations and even initially claimed as such, one or more features from a claimed combination can in some cases be excised from the combination, and the claimed combination may be directed to a sub combination or variation of a sub combination.

Various modifications to the implementations described in this disclosure may be readily apparent to those skilled in the art, and the generic principles defined herein may be applied to other implementations without departing from the spirit or scope of this disclosure. Thus, the claims are not intended to be limited to the implementations shown herein, but are to be accorded the widest scope consistent with this disclosure as well as the principle and novel features disclosed herein.

We claim:

1. A golf club head, comprising:
a striking face,
an aft portion extending aft from said striking face;
said aft portion comprising:
a sole defining a lower surface of said golf club head
and extending aft from said striking face;

11

a crown defining an upper surface of said golf club head and extending aft from said striking face; a skirt extending between said sole and said crown; a hosel extending from said crown; an interior cavity defined by said striking face, said sole, said crown, and said skirt; a recessed portion formed in an exterior of said aft portion; an aperture formed through said recessed portion of said aft portion, said aperture having an aperture length and an aperture width, wherein said aperture length is substantially larger than said aperture width; and a stiffening member affixed to said aft portion; wherein a portion of said stiffening member resides within said aperture; wherein said stiffening member comprises an internal portion and an external portion, wherein said external portion is oriented substantially perpendicular to said internal portion; wherein said internal portion extends through said aperture into said interior cavity and wherein said external portion abuts said recessed portion; wherein said stiffening member is constructed from carbon fiber reinforced polymer having fibers oriented in a lengthwise direction along said stiffening member, said lengthwise direction defined as a direction from a heel side to a toe side of said golf club head.

2. A golf club head, comprising:

a striking face, a sole defining a lower surface of said golf club head and extending aft from said striking face; a crown defining an upper surface of said golf club head and extending aft from said striking face; a skirt extending between said sole and said crown; a hosel extending from said crown; an interior cavity defined by said striking face, said sole, said crown, and said skirt; an aperture formed through said sole, said aperture having an aperture length and an aperture width, wherein said aperture length is substantially larger than said aperture width; and a stiffening member affixed to said sole; wherein a portion of said stiffening member resides within said aperture;

wherein said sole is constructed of a first material having a first density, said stiffening member is constructed of a second material having a second density, and wherein said second density is at least 30% less than said first density;

wherein said sole further comprises a retention protrusion extending in said interior cavity, wherein said stiffening member abuts said retention protrusion;

wherein said stiffening member comprises a first weight receptacle in an internal portion of said stiffening member and a weight member residing within said first weight receptacle;

wherein said weight member is configured to be placed within said first weight receptacle prior to said stiffening member being affixed to said sole.

3. The golf club head of claim 2, wherein said stiffening member comprises a stiffening member length measured along the major axis of said stiffening member, a stiffening member height measured perpendicularly to said stiffening member length and extending into said interior cavity, and a stiffening member width measured perpendicularly to said stiffening member length and said stiffening member height, wherein said stiffening member height is at least twice said

12

stiffening member width and wherein said stiffening member length is at least five times said stiffening member height.

4. The golf club head of claim 2, wherein said first material has a first modulus of elasticity, said second material has a second modulus of elasticity, and wherein said second modulus of elasticity is at least 30% greater than said first modulus of elasticity.

5. The golf club head of claim 2, wherein said stiffening member is constructed from carbon fiber reinforced polymer and affixed to said sole with adhesive.

6. The golf club head of claim 2, wherein said sole comprises a recessed portion in an exterior of said sole along said aperture.

7. The golf club head of claim 6, wherein said stiffening member comprises an internal portion and an external portion, wherein said external portion is oriented substantially perpendicular to said internal portion.

8. The golf club head of claim 7, wherein said internal portion extends through said aperture into said interior cavity and wherein said external portion abuts said recessed portion.

9. The golf club head of claim 2, wherein said stiffening member is constructed from carbon fiber reinforced polymer having fibers oriented in a lengthwise direction along said stiffening member, said lengthwise direction defined as a direction from a heel side to a toe side of said golf club head.

10. The golf club head of claim 2, wherein said stiffening member further comprises a second weight receptacle.

11. The golf club head of claim 2, further comprising a second stiffening member affixed to said crown, said second stiffening member arranged parallel to said stiffening member.

12. A golf club head, comprising:

a striking face, a sole defining a lower surface of said golf club head and extending aft from said striking face; a crown defining an upper surface of said golf club head and extending aft from said striking face; a skirt extending between said sole and said crown; a hosel extending from said crown; an interior cavity defined by said striking face, said sole, said crown, and said skirt;

an aperture formed through said sole, said aperture having an aperture length and an aperture width, wherein said aperture length is substantially larger than said aperture width; and

a stiffening member affixed to said sole; wherein a portion of said stiffening member resides within said aperture;

wherein said stiffening member comprises a stiffening member length measured along the major axis of said stiffening member, a stiffening member height measured perpendicularly to said stiffening member length and extending into said interior cavity, and a stiffening member width measured perpendicularly to said stiffening member length and said stiffening member height, wherein said stiffening member height is at least twice said stiffening member width and wherein said stiffening member length is at least five times said stiffening member height;

wherein said sole is constructed of a first material having a first modulus of elasticity, wherein said stiffening member is constructed of a second material having a second modulus of elasticity, and wherein said second modulus of elasticity is at least 30% greater than said first modulus of elasticity.

13

13. The golf club head of claim 12, wherein said first material has a first density, said second material has a second density, and wherein said second density is at least 30% less than said first density.

14. The golf club head of claim 12, wherein said stiffening member is constructed from carbon fiber reinforced polymer and affixed to said sole with adhesive, said carbon fiber reinforced polymer having fibers oriented in a lengthwise direction along said stiffening member, said lengthwise direction defined as a direction from a heel side to a toe side of said golf club head.

15. The golf club head of claim 12, wherein said sole comprises a recessed portion in an exterior of said sole along said aperture.

16. The golf club head of claim 15, wherein said stiffening member comprises an internal portion and an external portion, wherein said external portion is oriented substantially perpendicular to said internal portion.

14

17. The golf club head of claim 16, wherein said internal portion extends through said aperture into said interior cavity and wherein said external portion abuts said recessed portion.

18. The golf club head of claim 12, wherein said sole further comprises a retention protrusion extending in said interior cavity, wherein said stiffening member abuts said retention protrusion.

19. The golf club head of claim 12, wherein said stiffening member comprises a weight receptacle and a weight member residing within said weight receptacle.

20. The golf club head of claim 12, further comprising a second stiffening member affixed to said crown, said second stiffening member arranged parallel to said stiffening member.

* * * * *
